CLAIM

The ornamental design for a garment bag and luggage combination, as shown and described.

DESCRIPTION

FIG. 1 shows a top perspective view of the garment bag and luggage combination.

FIG. 2 shows a back perspective view thereof.

FIG. 3 shows a front elevation view thereof.

FIG. 4 shows a back elevation view thereof.

FIG. 5 shows a side elevation view thereof, other side being a mirror image thereof; and,

FIG. 6 shows a top plan perspective view thereof; and,

FIG. 7 shows a bottom plan perspective view thereof.

The broken lines shown in the drawings illustrate portions of a garment bag and luggage combination for illustration purposes only, and form no part of the claimed design.
